PHANTOM MAGNETO TELEPHONE SYSTEM

Charles Stanley Rhoads, Albany, N. Y., assignor
to American Telephone and Telegraph Com-
pany, a corporation of New York

Application May 21, 1943, Serial No. 437,891

10 Claims. (Cl. 179—15)

This invention relates to telephone systems, and more particularly to phantom circuits for telephone systems. Still more particularly this invention relates to arrangements for providing a phantom circuit from two telephone trunk circuits, the phantom circuit being equipped with a magneto set for auxiliary signaling.

A community dial office, generally unattended, is often connected to a master or operator office, generally attended, by a number of trunk circuits to enable subscribers in the area of the community dial office to communicate with the operator or subscribers in the area of the master or operator office and, via that office, with operators or subscribers at more remote points. The apparatus at the community dial office is usually arranged so that a subscriber may automatically select one of the trunk circuits by properly operating his dial set. It may happen, however, that the selectors or switches that control the selection and seizure of one of the trunks are busy or that all of the trunks are busy, in which case the operation of the dial set to establish a connection to the operator at the master office or to any of the subscribers reached via that office will be of no avail. Such a situation may be quite serious, especially during periods of emergency.

Accordingly it is an object of this invention to provide a phantom circuit by connection of apparatus to two telephone trunk circuits to enable a subscriber to signal either an operator at the master office or a subscriber in the area of the master office when all selectors or switches or trunks are busy. The phantom circuit of this invention involves additional equipment including a magneto telephone set arranged so that the operation of the magneto generator of the set will not interfere with signaling over the trunk circuits or cause false operation of the trunk circuits.

This invention will be better understood from the more detailed description hereinafter following when read in connection with the accompanying drawings, in which Figure 1 illustrates a master office and a community dial office interconnected by trunk circuits and provided with a magneto telephone set inserted in a phantom circuit for use with the trunk circuits as side circuits, and Fig. 2 shows schematically switching contacts controlled by the magneto generator of the magneto telephone set and arranged to prevent interference with and false operation of the equipment of the trunk circuits.

Referring to Fig. 1 of the drawings, two trunk circuits TK_1 and TK_2 of a group of similar trunk

circuits are shown interconnecting a community dial office CDO , usually unattended, and a master office MO at which one or more operators may be in attendance. Each of these trunk circuits 5 TK_1 and TK_2 may be employed for two-way signaling in a well known manner between the two offices and between subscribers connected to the two offices. A magneto telephone set MS may also be connected to the community dial office CDO and this set may be located in the area of the community dial office in the same manner that the subscribers' telephone sets SS_1 and SS_2 , for example, are so located. The magneto set MS is connected to the trunk TK_1 over parallel paths which include condensers C_1 and C_2 extending to the upper and lower portions of the primary windings of the transformer or repeating coil RC_1 . The magneto set MS is likewise connected to the trunk TK_2 by two parallel paths 10 including condensers C_3 and C_4 which extend to the upper and lower portions of the primary windings of the repeating coil or transformer RC_2 . The upper and lower windings of the battery and ground relay BG_1 associated with trunk TK_1 are connected to ground and battery B_1 , respectively, the paths to ground and battery including contacts 11 and 12 , respectively, of the switching device K . Similarly the upper and lower windings of the battery and ground relay BG_2 associated with trunk TK_2 are connected to battery B_2 and ground through the contacts 13 and 14 of the switching device K . When the switching device K is operated, the contacts 11 , 12 , 13 and 14 will be opened, in which case the upper and lower windings of relay BG_1 will be connected to ground and battery B_1 through the rectifying elements RK_1 and RK_2 , respectively, and the upper and lower windings of relay BG_2 will be similarly connected to battery B_2 and ground through the rectifying elements RK_3 and RK_4 , respectively. The switching device K may be hand-operated or it may, if desired, be controlled by the operation of the magneto generator MG of the magneto set MS , as will be described more particularly with respect to Fig. 2. However, whenever the device K is operated it controls the addition of the rectifiers RK_1 to RK_4 to the relays BG_1 and BG_2 of the two trunk circuits TK_1 and TK_2 . As will be explained 15 hereinafter, these rectifiers rectify the current of the magneto generator MG , enabling the rectified current to flow through the windings of the relays BG_1 and BG_2 unidirectionally and thereby prevent the release or "chatter" of these relays. The rectifiers therefore prevent false op-

eration of the switching apparatus controlled by these relays.

At the master office MO the upper and lower primary windings of the repeating coil or transformer RC_3 are connected by the parallel condensers C_5 and C_6 to one side of a jack J_0 which may terminate the phantom circuit and the upper and lower primary windings of the repeating coil of transformer RC_4 are similarly connected by condensers C_7 and C_8 , respectively, to the other side of the jack J_0 . These condensers are inserted in the circuit so that the alternating current produced by the magneto generator MG of the magneto set MS may alone cause the ring-down relay R_0 to be operated. The relay R_0 will be employed to light a lamp L_0 to signal the operator at the master office for auxiliary or emergency purposes. The operation of the phantom circuit of this invention will be described somewhat more fully hereinafter.

The trunk circuits TK_1 and TK_2 and the apparatus associated with these trunk circuits are of the usual type and they will be described only briefly. Whenever the subscriber having the telephone set SS_1 connected to the community dial office CDO desires to communicate with the operator at the master office MO, he will operate his dial set in the usual way. This will cause the selector or switching apparatus SW_1 to find an idle trunk such as TK_1 and seize the trunk to complete a path to the master office. When the trunk TK_1 is seized, current will flow from the battery B_3 through the lower winding of relay BS_1 , the lower secondary winding of repeating coil RC_1 , through the apparatus SW_1 to the telephone set SS_1 , and back over the upper conductor extending to the telephone set SS_1 , through the apparatus SW_1 and then through the upper secondary winding of the repeating coil RC_1 , the upper winding of relay BS_1 and ground. As relay BS_1 operates it establishes an obvious circuit for the operation of the relay BR_1 . When relay BR_1 operates, its two armatures reverse the connections to the conductors of trunk TK_1 , whereupon current will flow from battery B_1 over a circuit including contacts 12 of the switching device K, the lower winding of relay BG_1 , the lower primary winding of the repeating coil RC_1 , the lower armature and make contact of relay BR_1 , the upper conductor of trunk TK_1 , the upper primary winding of repeating coil RC_3 , the windings of relay P_1 , the lower primary winding of repeating coil RC_3 , the contacts 17 of the dial jack DJ_1 , the lower conductor of trunk TK_1 , the upper armature and make contact of relay BR_1 , the upper primary winding of repeating coil RC_1 , the upper winding of relay BG_1 , contacts 11 of the switching device K and ground. The flow of this current through the windings of the polarized relay P_1 is now in such a direction as to cause the relay P_1 to become operated. As relay P_1 becomes operated it completes a circuit to illuminate lamp L_1 , the circuit including the armature and make contact of relay P_1 , the lamp L_1 , the armature and back contact of relay R_1 , battery B_4 and ground. The illumination of the lamp L_1 will attract the operator's attention and she will therefore insert her plug PL into the jack J_1 which is associated with the lamp L_1 and trunk TK_1 to answer the call.

Upon the insertion of plug PL into jack J_1 a circuit will be established to operate relay R_1 , this circuit including the upper contact 19 of

jack J_1 , the winding of relay R_1 and ground. When relay R_1 operates it opens the circuit of lamp L_1 , thereby extinguishing the lamp L_1 . The operator's set will then be connected to the telephone set SS_1 , over trunk TK_1 to allow the operator and the subscriber to speak to each other. A subscriber's set such as SS_2 may likewise be connected to the operator at the master office through the equipment at the community dial office CDO and over trunk TK_2 in the manner already described in respect to telephone subscriber's set SS_1 .

The dial jacks DJ_1 and DJ_2 are shown connected to the trunks TK_1 and TK_2 , respectively.

15 The operator may connect her dial set to either of these jacks for connecting the trunk TK_1 , for example, to any one of the various subscribers' sets such as SS_1 , SS_2 , etc. When the dial set is connected to the jack DJ_1 , the dial pulses will be transmitted over the trunk TK_1 to operate the relay BG_1 in accordance with the pulses produced by the dial, whereupon the armature of the relay BG_1 will close its contact a number of times to control switching apparatus for selecting any desired one of the various telephone circuits such as SS_1 , SS_2 , etc. The switching apparatus has not been shown in detail as it is not required for an understanding of the invention.

The magneto set MS may be located on the

30 same premises as either the sub-set SS_1 or the sub-set SS_2 or at a different location. Whenever the subscriber's set SS_1 , for example, receives a busy signal after dialing the operator or any of the subscribers in the areas of the two 35 offices, the magneto generator MG may then be operated by hand for establishing a phantom circuit to the operator at the master office to attract her attention. Such a busy condition is not infrequent for it may arise whenever the selectors or switches such as SW_1 and SW_2 are busy or when the trunks TK_1 and TK_2 are busy. The hand generator MG will transmit an alternating current over the phantom circuit provided by the trunk circuits TK_1 and TK_2 to operate the relay R_0 at the master office, as already 40 stated. The interconnected circuit will include one path over the parallel condensers C_1 and C_2 and through the upper and lower primary windings of the repeating coil RC_1 , the two conductors of the trunk TK_1 , the two primary windings of repeating coil RC_3 , the parallel condensers C_5 and C_6 associated with the trunk TK_1 , the thermistor TH , the winding of relay R_0 , the contact 45 20 of jack J_0 , and then back over parallel circuits including condensers C_7 and C_8 associated with trunk TK_2 , the upper and lower primary windings of repeating coil RC_4 , the two conductors of trunk TK_2 , the two primary windings of the repeating coil RC_2 , the parallel condensers C_3 and C_4 to the generator MG. This 50 alternating current will cause relay R_0 to operate as already stated and complete an obvious circuit to illuminate lamp L_0 . The operator's attention will be attracted by lamp L_0 and upon the insertion of her plug PL into jack J_0 to answer the call, the lamp L_0 will be extinguished.

When plug PL is inserted into jack J_0 the operator's telephone set will be connected to the 55 magneto set MS to enable the operator and the subscriber controlling the magneto generator MG to talk with each other. The talking path at the master office will include the condensers C_5 and C_6 which are connected to trunk TK_1 , and the condensers C_7 and C_8 which are con-

ected to the trunk TK_2 . The talking path at the community dial office CDO will include the condensers C_1 and C_2 , which are connected to trunk TK_1 , and condensers C_3 and C_4 which are connected to trunk TK_2 . The telephone transmitter and receiver of the magneto set MS will be connected to this phantom circuit when the telephone receiver is removed from its switchhook SH.

It is noted that the upper terminal of the magneto generator MG is connected through parallel paths including condensers C_1 and C_2 and the upper and lower windings of relay BG_1 to ground and battery B_1 , respectively, and that the lower terminal of magneto generator MG is connected to the upper and lower windings of relay BG_2 and battery B_2 and ground, respectively. The alternating current of magneto generator MG may therefore traverse the windings of both relays BG_1 and BG_2 and cause their false operation. These relays will alternately open and close their respective make contacts in response to the generated current. As the make contacts of these relays are closed, the existing connections (not shown) established through the armatures of these relays to trunks TK_1 and TK_2 will be opened and hence the trunks TK_1 and TK_2 may be released. Hence existing communication over trunks TK_1 and TK_2 will be terminated. In other words, the operation of the magneto generator MG may cause the relays BR_1 and BR_2 to "chatter" and thereby interfere with talking or signaling over the two trunks TK_1 and TK_2 . Such a condition is undesirable. This undesirable condition, however, may be overcome by simply operating switching device K.

When the switching device K is operated, it will insert rectifying elements into the circuits of the windings of relays BG_1 and BG_2 . With the device K operated, contacts 11 and 12 will be opened and rectifiers RK_1 and RK_2 will be connected between the upper and lower windings of relay BG_1 and ground and battery B_1 , respectively. Similarly contacts 13 and 14 will be opened, interposing rectifiers RK_3 and RK_4 in the circuits between the upper and lower windings of relay BG_2 and battery B_2 and ground, respectively. Thus, by so operating device K, current will now flow unidirectionally through the upper windings of relays BG_1 and BG_2 over a circuit which includes rectifier RK_1 , the upper winding of relay BG_1 , condenser C_1 , the generator MG, condenser C_3 , the upper winding of relay BG_2 , rectifier RK_3 , battery B_2 and ground. Current will also flow unidirectionally through the lower winding of relays BG_1 and BG_2 over a circuit which includes battery B_1 , rectifier RK_2 , the lower winding of relay BG_1 , condenser C_2 , generator MG, condenser C_4 , the lower winding of relay BG_2 , rectifier RK_4 and ground. The unidirectional currents now traversing both windings of relays BG_1 and BG_2 will be superimposed upon the direct currents previously supplied to these windings by batteries B_1 and B_2 . Thus an increased current will traverse the windings of relays BG_1 and BG_2 and these relays will be held operated while the hand generator MG is operated. These relays remaining operated they will hold the trunks TK_1 and TK_2 connected to the subscribers' sets such as SS_1 and SS_2 and not interfere with communication over the two trunk circuits.

The condensers C_1 and C_2 provide a low impedance path between generator MG and trunk

TK_1 for the alternating current generated and condensers C_3 and C_4 provide a low impedance path between trunk TK_1 and relay R_0 so that only the generated current may actuate relay R_0 . The return path for the generated current includes condensers C_7 and C_8 , trunk TK_2 and condensers C_3 and C_4 . The rectifying elements RK_1 to RK_4 prevent the flow of alternating current through the windings of the relay apparatus common to trunk TK_1 or trunk TK_2 except in rectified form. Thus alternating current will be transmitted over the trunks acting as transmission paths extending between the two offices, but the trunk control apparatus will receive only direct current.

The rectifiers RK_1 to RK_4 interposed in the circuits between the hand generator MG and the windings of relays BG_1 and BG_2 provide in effect a full wave rectifying circuit. Both halves of each cycle of alternating current produced by the generator MG will be rectified and the rectified current will be added to the battery currents previously flowing through these relay windings. Thus the rectified currents and the battery currents will be caused to aid each other, increase the holding action of relays BG_1 and BG_2 and prevent their "chattering." This is an important feature of this invention.

Fig. 2 shows schematically an arrangement for inserting the rectifiers RK_1 to RK_4 of Fig. 1 into their respective circuits upon the operation of the hand generator MG. The crank of the hand generator MG when rotated controls a cam 29, which in turn may move the insulating bar 30 to the left so as to open all of the contacts 31, 32, 33 and 34 simultaneously. Contacts 31 and 32 bridge the rectifiers RK_1 and RK_2 , respectively, and contacts 33 and 34 bridge rectifiers RK_3 and RK_4 , respectively. When the arm 30 is caused to move to the left in response to the rotation of the crank of the generator MG, the contacts 31 to 34 will be opened, thereby inserting the rectifiers RK_1 to RK_4 in their respective paths, as already described hereinabove with respect to Fig. 1. At the same time contact 35 will be closed to establish a path between the hand generator MG and the condensers C_1 and C_2 . The contact 35, therefore, interposes the hand generator MG in series between the parallel condensers C_1 and C_2 and the parallel condensers C_3 and C_4 . These condensers are connected to the trunk circuits as shown in Fig. 1. The switching arrangement of Fig. 2 is automatic in operation and opens the bridge circuit to the rectifiers just as soon as the crank of generator MG is properly rotated. Although the arrangement of Fig. 2 illustrates how the magneto generator MG may simultaneously close a plurality of contacts such as 31 to 35, it will be understood that the cam device 29 may close but one contact which in turn may control the operation of a relay (not shown), the relay controlling the contacts 31 to 35 which shunt the rectifiers RK_1 to RK_4 . The relay obviously may be located either at the station of the magneto telephone set MS or at the community dial office CDO. The contacts 12-14 associated with the relay may be adjacent to the relay or remote therefrom, as desired.

Although it has been stated that the magneto set may be operated whenever a busy condition develops on the trunk circuits between the two offices, the magneto set may also be used even when the trunk apparatus is idle. The magneto phantom circuit provides an additional path be-

tween the two offices for special use both for signaling and talking during emergencies. The cost of the equipment required to set up the phantom circuit is quite small. The additional equipment is simple and may be appended to the trunk apparatus whenever desired. The magneto phantom circuit will be operable whether or not the trunk circuits are transposed with respect to each other.

Although this invention has been disclosed in certain specific arrangements which are deemed desirable, it will be obvious that the general principles herein set forth may be embodied in many other organizations, widely different from those illustrated, without departing from the spirit of the invention as defined in the appended claims.

What is claimed is:

1. In a telephone system, the combination of a manual office and a community dial office connected to each other by a pair of trunks, two relays each connected to one of said trunks for controlling the connection of the trunk to subscribers' circuits, a magneto telephone set including a magneto generator connected to said trunks as a phantom circuit, and means for preventing the magneto generator from falsely operating the said relays.
2. In a telephone system, the combination of two trunks, two repeating coils one terminating each trunk, two relays each connected to the midpoint of one of the repeating coils, a magneto telephone set including a magneto generator connected between the midpoints of said repeating coils so that said trunks may provide a phantom circuit for said magneto set, a plurality of rectifying elements, and means responsive to the operation of the magneto generator for inserting said rectifying elements in series with the windings of said relays so that only unidirectional current may flow through the windings of said relays.
3. In a telephone system, the combination of a telephone line, a relay connected to said line, a magneto generator, means for connecting said magneto generator to said line to energize the winding of said relay, a rectifying element, and means responsive to the operation of said magneto generator to connect said rectifying element in series with the winding of said relay so that only unidirectional current may flow through said relay windings.
4. In a telephone system, the combination of a relay having two windings, two rectifying elements, a telephone line connected to the windings of said relays, a magneto generator, and means responsive to the operation of said generator for connecting said rectifying elements to the windings of said relay so that only unidirectional current may flow therethrough.
5. In a telephone system, the combination of two trunks, two repeating coils each terminating one of said trunks, two relays one associated with each trunk and connected to the midpoint of the repeating coil of the associated trunk, a magneto telephone set including a magneto generator connected between the midpoints of the repeating coils of both trunks so that said trunks may form the side circuits of a phantom circuit, a plurality of rectifying elements, and means responsive to the operation of said magneto generator for inserting said rectifying elements in circuit with said relay windings so that only unidirectional currents may traverse the windings of said relays.
6. In a telephone system, the combination of two trunks, two repeating coils each terminating one of said trunks, switching apparatus for said trunks, said switching apparatus including a relay for each trunk connected to the midpoint of the repeating coil associated with said trunk, a magneto telephone set including a magneto generator connected between the midpoints of the repeating coils associated with both trunks so that said trunks may provide a phantom circuit for said magneto set, means responsive to the operation of the generator of said magneto set for transmitting only rectified current through the windings of said relays, and apparatus controlled by the current produced by said magneto generator.
7. In a telephone system, the combination of a pair of trunks interconnecting two offices, a magneto telephone set including a magneto generator connected between both trunks at one of the offices so as to provide a phantom circuit, signal responsive means connected between both trunks at the other of the offices to complete the phantom circuit, switching apparatus connected to each trunk, and means to prevent the operation of said switching apparatus by said magneto set.
8. In a telephone system, the combination of a pair of trunks interconnecting two offices, a telephone set including a ringing generator connected between both trunks at one of the offices, signaling apparatus connected between both trunks at the other of the offices, said telephone set and said signaling apparatus providing with said trunks a phantom circuit, switching apparatus connected to each trunk, and means to prevent the ringing generator of the telephone set from falsely operating said switching apparatus.
9. In a telephone system, the combination of a pair of trunks interconnecting two offices, a telephone set including a ringing generator connected between both trunks at one of the offices, signaling apparatus connected between both trunks at the other of the offices, said telephone set and said signaling apparatus providing with said trunks a phantom circuit, switching apparatus connected to each trunk, and means responsive to the operation of the ringing generator of said telephone set to prevent the release of the switching apparatus by the current of said ringing generator when said switching apparatus is operated.
10. In a telephone system, the combination of two telephone offices connected to each other by a pair of trunks, a plurality of subscribers' circuits, two relays each connected to one of said trunks for controlling the connection of the associated trunk to one of the subscriber circuits, a magneto telephone set including a magneto generator which may be connected to said trunks as a phantom circuit when said trunks are busy, and means to prevent said magneto generator from falsely operating said relays.
